inwardly extending and rigidizing rib 15. The ends of longitudinal members 16 and 17 are secured to the side walls of housing 14. The side walls of housing 14 are provided with a transverse apertured mounting flange or plate 20 which is secured to the side walls of housing 14.

UNITED STATES PATENT OFFICE

2,609,280

FUEL MIXING DEVICE

Alva D. Cremeen, Searcy, Ark.

Application November 29, 1948, Serial No. 62,441

1 Claim. (Cl. 48—180)

1

This invention relates to an internal combustion engine, and more particularly to a turbulence manifold for interposition between the intake manifold and a pair of carburetors.

The object of the invention is to provide a turbulence manifold for interposition between the intake manifold of an internal combustion engine and a pair of carburetors which will insure that the air-fuel mixture will be transmitted to the combustion chambers in its most efficient vaporized state with increased velocity.

Another object of the invention is to provide a turbulence manifold for an internal combustion engine which will give the engine superior motor performance at all speeds, and which will decrease fuel consumption without sacrificing any of the other added engine performance.

A further object of the invention is to provide a turbulence manifold which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a plan view of a turbulence manifold according to the present invention, showing the adaptation thereof with respect to a pair of carburetors and the intake manifold of an internal combustion engine;

Figure 2 is a side elevational view of the turbulence manifold;

Figure 3 is a sectional view taken on the line 3—3 of Figure 4;

Figure 4 is a sectional view taken on the line 4—4 of Figure 3;

Figure 5 is a plan view of the blanks from which the deflector plate is made.

Referring in detail to the drawings, the numerals 10 and 11 designate a pair of conduits leading from a pair of carburetors for conveying a fuel-air mixture from the latter. The numeral 12, Figure 1, designates a portion of an intake manifold of an internal combustion engine. Interposed between the conduits 10 and 11 and the intake manifold 12 is a turbulence manifold 13 through which the air-fuel mixture from the carburetors passes prior to its entry into the intake manifold 12.

The turbulence manifold 13 comprises a hollow housing 14 substantially cylindrical shape in cross section having its opposite ends 15 and 16 open and registering with the conduits 10 and 11. For securing the end 15 of the housing to the conduit 10, a transverse apertured mounting face or plate

17 projects from the end 15 of the housing and is arranged in opposed relation with respect to a mounting face 18 on the conduit 10. Suitable bolt-and-nut assemblies 19 connect the mounting faces or flanges 17 and 18 together. The other end 16 of the housing 14 is secured to the conduit 11 by a transverse apertured mounting flange or plate 20 which is arranged in opposed relation with respect to a mounting plate or flange 21 on the conduit 11 and connected to the latter by bolt-and-nut assemblies 22.

Arranged intermediate the ends of the housing 14 is an opening 23 which registers with the intake manifold 12 and permits the air-fuel mixture 15 to enter the latter. The housing 14 is provided with a mounting plate or flange 24 adjacent the opening 23 and the plate 24 is apertured, as at 9, for receiving bolt-and-nut assemblies 25 in order to secure the housing 14 to the intake manifold 12.

20 The housing 14 is provided with a means for setting up a predetermined pattern of accelerated turbulence in the air-fuel mixture prior to its entry into the intake manifold 12. This means comprises a deflector plate 26 substantially S-shaped in cross section arranged within the housing 14 and provided with a transversely-disposed apertured tab 27 for receiving a screw 28 to fasten the plate 26 to the housing 14. The plate 26 is formed with a web having its ends bent or curved 25 in opposite directions as at 29. In Figure 5, there is shown the blank 30 from which the deflector plate 26 is made. Thus, there is shown the apertured tab 27 which is bent along the line 31, and the end portions 29 thereof which are adapted to be bent in opposite directions along the line 32.

35 By using the turbulence manifold with dual carburetors, the thrust augmentation on all makes of car and truck engines will be increased. The deflecting plate 26 eliminates wet spots in 40 the air-fuel mixture which passes through the housing 14. Further, the plate will set up a predetermined pattern of accelerated turbulence in the air-fuel mixture, so that it will be transmitted to the engine combustion chambers in its most 45 efficient vaporized state with increased velocity. The plate 26 deflects each air-fuel stream downward, and at the same time breaks down the fuel into more minute particles giving superior motor performance in all respects.

50 As many embodiments may be made of this inventive concept, and as many modifications may be made in the embodiment hereinbefore shown and described, it is to be understood that all matter herein is to be interpreted merely as 55 illustrative and not in a limiting sense.

I claim:

In a turbulence manifold for internal combustion engines, the combination which comprises an elongated substantially cylindrical housing having inlet carburetor openings with attaching flanges on the ends and with said flanges positioned in a common plane which plane is parallel to the longitudinal axis of the housing, the axes of said carburetor openings being substantially perpendicular to said axis of the housing, said housing also having an outlet intake manifold opening with an attaching flange thereon positioned between said carburetor openings, the area of said housing being less at the point where the intake manifold opening is positioned than at the ends where the carburetor openings are positioned, and a deflector, substantially S-shaped in cross section, having an intermediate web positioned transversely of said housing and having oppositely curved ends on said web mounted on the inner surface of the wall of the housing opposite to the

10 15

5

wall in which the said intake manifold opening is positioned, said deflector positioned in alignment with said intake manifold opening whereby maximum turbulence of air and gas mixtures passing through said housing is produced.
